UNITED STATES PATENT OFFICE.

EDWARD E. GALLE, OF LOS ANGELES, CALIFORNIA.

DESIGN FOR A PASTE POT.

60,401.

Specification for Design.

Patented Feb. 14, 1922.

Application filed September 30, 1920. Serial No. 413,928. Term of patent 14 years.

To all whom it may concern:

Be it known that I, EDWARD E. GALLE, a citizen of the United States, residing at Los Angeles, in the county of Los Angeles and State of California, have invented a new and original and ornamental Design for a Paste Pot, of which the following is a specification, reference being had to the accompanying drawing, forming part thereof.

In the drawing, Fig. 1 is a plan view of a jar embodying my design and Fig. 2 is a side elevation of the jar shown in Fig. 1.

I claim:

The ornamental design for a paste pot, as shown.

EDWARD E. GALLE.
